(57) **CLAIM**

We claim the ornamental design for a cartridge label, as shown and described.

DESCRIPTION

This patent contains at least one drawing executed in color. Copies of this patent with a color drawing will be provided by the Office upon request and payment of the necessary fee. FIG. 1 is a top plan view of the first embodiment of a cartridge label, showing our new design; FIG. 2 is a side elevational view thereof; FIG. 3 is a front elevational view thereof; FIG. 4 is a top plan view of the second embodiment; FIG. 5 is a top plan view of the third embodiment; FIG. 6 is a top plan view of the fourth embodiment; FIG. 7 is a top plan view of the fifth embodiment; FIG. 8 is a top plan view of the sixth embodiment; FIG. 9 is a top plan view of the seventh embodiment; FIG. 10 is a top plan view of the eighth embodiment; and, FIG. 11 is a top plan view of the ninth embodiment. The broken lines shown in the drawings illustrate portions of the cartridge label that form no part of the claimed design.
